UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM.

Application filed June 17, 1922. Serial No. 569,109.

The present invention relates to an improvement in looms.

The object of the invention is to reorganize and improve the construction of looms, more particularly with respect to the knock-off lever and the connections between it and the belt shipper. To the above ends the present invention consists in the improved loom hereinafter described and particularly defined in the claims.

In the accompanying drawings illustrating the preferred form of the invention, Fig. 1 is an end elevation of a part of a loom showing the present construction adapted for use in connection with a belt approaching the loom from the floor; Fig. 2 is a similar end elevation of a part of a loom showing the construction adapted for use with a belt approaching the loom from overhead shafting; Fig. 3 is a plan view of the construction shown in Fig. 2; and Fig. 4 is a front elevation of the knock-off lever and the crank bracket applied thereto, drawn on an enlarged scale.

The illustrated embodiment of the invention is described as follows: The end frame 10 of the loom is of the usual construction. The lay shaft 11 is mounted in bearings on the frames of the loom, and is provided in addition with an out-board bearing 12 supported on the bearing bracket 13. The shaft carries the tight pulley 14 and the idler 15. The bracket 13 is provided with an extension 16, to which is bolted the belt shipper support 17. The belt shipper 18 is mounted in bearings in the support 17, and on its forward end it is provided with a clamp 19, which engages a slot 20 in the shipper casting 21, secured to the knock-off lever 22 by means of the bolt 23. When the knock-off lever is moved from the position shown in Fig. 3 to the position 24 indicated in dotted lines in said figure, the shipper is rocked in its bearings to throw the belt from the idler to the tight pulley. On the rear end of the belt shipper is mounted an arm 25, being secured to the shipper 18 by two set screws 26. With a belt running from the floor, as shown in Fig. 1, a shipper fork 27 is used, it being directly secured to the arm 25 by the pin 28 and the bolt 29. The fork 27 is provided with a slot 30, so that it may be adjusted with respect to the arm 25 in correct position to engage the belt 31.

When an overhead drive is used, an extension member 32 is attached to the arm 25, and to the end of the extension member 32 is attached the fork 27.

It will be noted that the position of the fork when used in connection with the extension member 32 on an overhead drive arrangement is located above the axis of the shipper 18, while when the fork is used on a floor drive it is located below the axis. This is conveniently secured by providing the shipper casting 21 with a second slot 33, which is adapted to receive the crank 19 of the shipper 18 when the floor drive arrangement is used. The arm 25 is attached to the shipper 18 in one position when one drive is used, and in another position when the other drive is used. It will thus be seen that the shipper casting, the shipper, the arm 25, and the belt fork 27, are identical for both overhead and floor drives, and that all that is necessary to be done in setting up the shipper for use on an overhead drive is to provide the additional extension member 32, and to arrange the crank of the shipper so that it engages the upper slot in the shipper casting. When setting up for the floor drive, the fork will be attached directly to the arm 25, and the crank of the shipper will be received in the lower slot 33 of the shipper casting on the knock-off lever. This provides a convenient arrangement for the manufacture of looms adapted either for floor or overhead drive, as all parts for the two constructions are identical except that with the overhead drive an additional extension member is used.

The end of the extension member attached to the shipper arm 25 is the same in shape as the end of the belt fork, so that the extension member may be substituted for the belt fork for attachment to the shipper arm. The other end of the extension member is the same in form as the end of the shipper arm, so that it is adapt'd to support the fork 27 in the same manner and by the same mode of attachment as the shipper arm is adapted to support it.

When the extension member is used, it may be considered either as an extension of the shipper arm, or as an extension of the belt fork, or as an additional independent member. The claims will be read and understood in view of this statement.

Having this described the invention, what is claimed is:

1. A loom having, in combination, a frame, a knock-off lever mounted on the frame, a belt shipper, a belt fork, and an arm mounted on the belt shipper, the belt fork being adapted to be secured directly to the arm for floor drive arrangement, or to an extension member interposed between the fork and the arm for overhead drive arrangement, said shipper being provided with a crank, and the knock-off lever being provided with two slots, the one adapted to receive the crank when the shipper is arranged for overhead drive, and the other being adapted to receive the crank when the shipper is arranged for floor drive.
2. A loom having, in combination, a frame, a knock-off lever mounted on the frame, and a belt shipper provided with a crank, the knock-off lever being provided with two slots for engagement with the crank of the belt shipper in either one of two positions, one being for use with the shipper arranged for floor drive, and the other being for use with the shipper arranged for overhead drive.
3. A loom having, in combination, a frame, a knock-off lever provided with two slots, a belt shipper having a crank adapted to engage the one or the other of the two slots of the knock-off lever, an arm mounted on the belt shipper, an extension member

secured to the arm, and a belt fork mounted on the end of the extension member when the loom is arranged for overhead drive, and adapted to be mounted directly on the arm when the loom is adapted for floor drive, said extension member and belt fork both being provided with similar ends 40 adapted for similar support on the belt shipper arm.

4. A loom having, in combination a frame, a knock-off lever mounted on the frame, a belt shipper provided with a crank 45 adapted to engage the knock-off lever in one operative position when the loom is arranged for overhead drive, and to engage the knock-off lever in another operative position when the loom is arranged for floor drive, said shipper being provided with an arm adapted to carry a belt fork of two different kinds, the one extended to engage the belt above the loom pulley, and the other to engage the belt below the loom pulley.

5. A loom having, in combination, a frame, a knock-off lever mounted on the frame and provided with a crank-opening, a belt shipper comprising a rock shaft having a crank on its front end and a belt fork 60 on the rear end, the crank being received in the crank-opening of the knock-off lever and operated thereby to rock the shipper and fork to move the belt from tight to loose and loose to tight pulleys.

JONAS NORTHRUP.
